UNITED STATES PATENT OFFICE.

WILLIAM TAYLOR COLLINS, DECEASED, LATE OF TALLAHASSEE, FLORIDA, BY JOHN WAILES DE MILLY, ADMINISTRATOR, OF TALLAHASSEE, FLORIDA.

PERFORATING AND CUTTING DEVICE FOR MULTIGRAPHS.

1,374,062.

Specification of Letters Patent.

Patented Apr. 5, 1921.

Application filed March 15, 1920. Serial No. 365,976.

To all whom it may concern:

Be it known that I, JOHN WAILES DE MILLY, a citizen of the United States, residing at Tallahassee, in the county of Leon 5 and State of Florida, administrator of the estate of WILLIAM TAYLOR COLLINS, late a citizen of the United States, and a resident of Tallahassee, Florida, do declare that the said WILLIAM TAYLOR COLLINS has invented 10 certain new and useful Improvements in Perforating and Cutting Devices for Multigraphs, of which the following is a specification.

This invention relates to a device for cutting 15 and perforating sheets of paper which is in the form of an attachment so that it may be applied to a multigraph machine of the ordinary construction for perforating and cutting the paper as it leaves the machine.

It is a purpose of this invention to provide an attachment of the above described character in which the cutting and perforating blades are associated with supporting 20 disks to permit of the removal and substitution of other disks when they become worn or broken.

It is also a purpose of this invention to provide a roller which coacts with the blades 25 in effecting the perforating and cutting of the sheets of paper, such roller comprising two sections which are held in spaced relation to provide a slot for the reception of the cutting edge of the blades, and are adjustable with respect to each other to provide a groove of a predetermined width to accommodate a particular blade.

I will describe one form of device embodying this invention and two forms of 30 blades, and will then point out the novel features thereof in claim.

In the accompanying drawings:

Figure 1 is a view showing in side elevation a conventional form of paper feeding 35 means for a multigraph machine having applied thereto one form of perforating and cutting device embodying this invention.

Fig. 2 is a vertical sectional view taken on the line 2—2 of Fig. 1.

50 Fig. 3 is a view similar to Fig. 2 showing a cutting blade substituted for the perforating blade shown in Fig. 2.

Fig. 4 is an enlarged detail view of the perforating blade.

Figs. 5 and 6 are detail views of the sections comprised in the blade carrying roller.

Figs. 7, 8, 9 and 10 are detail views of the coacting feeding rollers.

Similar reference characters refer to similar parts in each of the several views.

Referring specifically to the drawings and particularly to Fig. 1, F designates a frame in which is journaled a pair of superposed shafts S and S' carrying coacting feed rollers R for effecting the feeding of sheets 65 of paper from a multigraph machine.

The device embodying the subject matter of this invention comprises, a large feed roller designated generally at A and including a section 15 having a collar 16, and a section 17 which is adapted to be clamped with the section 15 for supporting a perforating blade B or a cutting blade B' therebetween. As illustrated to advantage in Figs. 5 and 6, the sections 15 and 17 are of disk formation 75 and are formed with axial openings through which the shaft S is adapted to extend. They are also provided with other openings through which screws 18 extend for clamping the two sections together. The collar 16 of the section 15 carries a set screw 19 which is adapted to engage the shaft S for locking the roller as a unit upon the shaft.

As shown in Fig. 4, the perforating blade B is of disk formation with the marginal edge thereof serrated to provide teeth 20. This blade is also formed with openings for the reception of the screws 18 and the shaft S.

As shown in Fig. 1, the roller A coacts with a relatively small roller A' which consists of two sections 21 and 22 connected to each other by screws 23 and fixed to the shaft S' by a set screw 24. As illustrated to advantage in Fig. 10, the sections of the roller A are maintained in spaced relation by a 95 ring 25, such ring being of a diameter to fit within the area defined by the screws 23 so that no additional means is necessary for securing the ring in proper position between the sections.

100 By this arrangement it will be seen that an annular slot is provided within the roller A' and that the roller in the applied position as shown in Figs. 1, 2 and 3 receives the cut-

ting edge of the blade B or B' so as to allow the peripheries of the two rollers to contact with each other. The width of the slot in the roller A' can be varied in accordance 5 with the thickness of the ring 25 so that blades of various widths may be used with the roller A at the same time securing the proper coaction between the two rollers.

In operation, the sheets of paper are fed 10 between the rollers R and the rollers A and A' and during this operation the teeth 20 of the blade B successively pierce the sheet of paper and thereby perforate the same. When the cutting blade B' is employed it 15 coacts with the roller A in a manner identical to the blade B because of the continuous cutting edge a separating of the paper is secured.

Although I have herein shown and de- 20 scribed only one form of perforating and cutting device embodying this invention, it is to be understood that various changes and modifications may be made herein without

departing from the spirit of the invention and the spirit and scope of the appended 25 claim.

What I claim is:

A device of the character described comprising, a roller including combination sections, a blade secured between the sections and having the cutting edge thereof projecting beyond the periphery of the sections, means for securing the sections together, and a second roller comprising sections, fastening members extending through the sections 30 at intervals and securing the sections together, and a ring interposed between the sections of the second roller and disposed within the area defined by the fastening members for maintaining the sections in 35 40 spaced relation to accommodate the cutting edge of the blade.

JOHN WAILES DE MILLY,
Administrator of the estate of William Taylor Collins, deceased.
